UNITED STATES PATENT OFFICE

LAWRENCE H. HEUER, OF DETROIT, MICHIGAN, ASSIGNOR TO L. A. YOUNG SPRING AND WIRE CORPORATION, OF DETROIT, MICHIGAN

RETAINING DEVICE

Application filed December 5, 1931. Serial No. 579,152.

The main object of my invention is to provide a retaining device that is simple and economical in construction yet highly efficient and effective in operation.

5 Another object is to provide a key for grooved bolts or pins or the like, which may be quickly applied and is very strong and secure.

Objects relating to details and economies 10 of my invention will appear from the description to follow. The invention is defined and pointed out in the claims.

A structure which is a preferred embodiment 15 of my invention is illustrated in the accompanying drawing, in which:

Fig. 1 is a side elevation of a retaining device embodying my invention, the parts secured being indicated by the dotted lines.

Fig. 2 is a view similar to Fig. 1, a portion 20 of the end of the bolt being broken away and shown in longitudinal vertical section, taken on a line corresponding to line 2—2 of Fig. 3.

Fig. 3 is a transverse section taken on line 25 3—3 of Figs. 1 and 2.

Fig. 4 is a view similar to Fig. 3 showing the key before closing, and

Fig. 5 is a perspective view of the key before applying.

30 Referring to the drawing, numeral 1 indicates a pin or bolt having an enlarged head 2 at one end thereof and a peripheral groove 3 near the other end. The groove 3 is provided with the key 4 of bendable metal 35 having a semi-circular flat central portion 5 opposite the opening 6 between the ends 7 thereof.

The flat central portion 5 constitutes a tongue engageable with the groove 3, the flat 40 portion being disposed within the groove 3 as illustrated. The opening 6 between the ends 7 is large enough to permit the key to be slipped onto the pin until the flattened portion registers with the groove. The ends 45 7 are then drawn toward each other so as to substantially close the opening 6 and to bring the relatively wide unflattened portions 8 of the key into supporting engagement with the pin drawing the portion 5 into the groove. The portions 8 being rel-

atively wider than the groove 3 engage the edges thereof and prevent the key from slipping relative to the groove. Rattling of the key in the groove is also obviated and this is a decided advantage when the bolt 55 is used in automotive constructions such as conventional automobiles and the like.

While the keys, as described above, may be made in any suitable manner, I prefer to make them in the following manner. 60 Wire stock of the proper size and material is first formed into a coil or spiral and the loops thereof are cut from the spiral and fed to a suitable press to flatten the semi-circular portions 5, as described above. The enlarged portions 8 may be flattened slightly as illustrated to bring the ends 7 of the washer into annular alinement with each other.

My improved retaining means may be 70 adapted to secure the members 9 in assembled relation in an efficient manner and without fear of the loosening or rattling of the retaining means in use.

It is obvious that various changes and 75 modifications may be made in the details of construction and design of the above specifically described embodiments of my invention without departing from the spirit thereof; such changes and modifications being restricted only by the scope of the following claims.

Having thus described my invention, what I claim as new and desire to secure by Letters Patent is:

1. A device of the class described, comprising a split ring having a flattened semi-circular tongue-like portion opposite the opening between the ends thereof, which opening may be closed after the ring is 90 passed over a stud and said flattened tongue-like portion disposed in a peripheral groove therein by drawing said ends together the end portions being of sufficient thickness to prevent their entering the groove.

2. An article of the class described, comprising a bolt provided with a peripheral groove, and a split metal key having a groove engaging portion opposite the opening between the ends thereof disposed in said 100

groove, the ends of said key being drawn together to substantially close said opening, the end portions of said key being wider than said groove, whereby to hold said key in said groove.

3. An article of the class described, comprising a bolt provided with a peripheral groove, and a split key having a flattened portion disposed in said groove and an unflattened portion wider than said groove engaging the edges thereof and preventing lateral movement of said key relative to said groove.

4. A locking key for bolts or pins having annular grooves therein in the form of a split ring having an intermediate portion of a thickness permitting its entrance to the groove of the pin to be secured, and end portions of a thickness exceeding the width of the groove so that the end portions may be clamped upon the pin and act to draw and retain the intermediate portion within the groove.

5. A locking key for bolts or pins having annular grooves therein in the form of a split ring having a portion of a thickness permitting its entrance to the groove of the pin to be secured, and a portion of a thickness exceeding the width of the groove so that the last named portion may be clamped upon the pin and act to draw and retain the first named portion within the groove.

6. A device of the class described, comprising a split ring having a flattened portion opposite the opening between the ends thereof, which opening may be closed after the ring is passed over a stud and said flattened portion disposed in a groove therein by drawing said ends together, the end portions being of sufficient thickness to prevent their entering the groove.

In witness whereof I have hereunto set my hand.

LAWRENCE H. HEUER.
